TENSION HOLDER

Joseph F. Fauner, Irvington, N. J.

Application August 15, 1942, Serial No. 455,005

6 Claims. (Cl. 211—120)

This invention relates to tension or snap holders in general, and particularly to tension holders known as fingers, and finding employment in connection with flag bags for flags and pennants used on board of ship for signaling and other purposes.

Snap holders or fingers for flag bags are well known, and they are designed for tensionally retaining rings and hooks, by means of which the cords, from which flags or pennants are suspended, are joined with one another. Usually one or two batteries of such fingers are employed with one of such flag bags, which latter comprises a box-like structure in which flags and pennants are stored, and from which they are to be rapidly hoisted in the desired order when signals are to be given.

One of the major requirements of such fingers is to facilitate the ready insertion and accommodation of flag rings and flag hooks, as they are rapidly handled by the signal crew, and to hold them in place under sufficient tension to prevent their accidental disengagement. The fingers must also permit an instant removal of such rings and hooks when desired. The outer structure of the fingers is preferably so designed as to prevent as much as possible any damage to the flags and pennants, in the event the latter come in touch with the fingers. In order to meet this last requirement the presently used flag bag fingers are hand-made by welding or brazing, and their corners are hand-rounded. Consequently their cost is very high. Moreover, their bodies are closed and permit the accumulation of water and ice, whereby their usefulness becomes very much impaired.

The present invention represents a marked improvement over such old type devices, one of the features of the instant development being the prevention of an accumulation of water or ice within the finger structure. Another advantage resides in the simplicity and effectiveness of my ring and hook holding instrumentalities, which positively but yieldingly engage the rings and hooks when the latter are in their stored or locked position. The device also permits a ready removal of stich rings and hooks since its holding instrumentalities are designed to reduce friction to a minimum. At the same time the construction of these instrumentalities is such as to prevent their deformation and fatigue in their tensional function, although they are frequently subjected to severe strains caused by the rapid insertion and removal of the rings and hooks normally held in the fingers.

The prime object of this invention therefore is to provide a finger construction which is simple, inexpensive and yet most effective, and wherein its parts are maintained in their intended working condition for an indefinite period of time.

The foregoing and still further objects of the present invention will become more fully apparent from the ensuing description in connection with the accompanying drawing, which latter illustrate the presently preferred form of my device, and wherein:

Fig. 1 denotes a top portion of a flag bag equipped with my finger construction;

Fig. 2 is a top view of a battery of my fingers;

Fig. 3 is an enlarged, longitudinal cross section through a finger;

Fig. 4 is a bottom view of a finger;

Fig. 5 is a transverse section through two fingers, taken on line 5—5 of Fig. 3;

Fig. 6 is a transverse cross section through two fingers, taken on line 6—6 of Fig. 3; and

Fig. 7 is a perspective, detail view of my friction-reducing tension means used in my fingers.

Referring now specifically to Fig. 1, numeral 10 denotes the upright of a framework forming a part of a flag box or flag bag, and from which upright extends at an incline a portion of a top frame 12, supporting sides 13 of the flag bag. Secured between end members 12 and attached to uprights 10 within the flag bag is a supporting plate 14, provided with a name plate 15, upon which are marked letters, numbers and insignias of the different flags and pennants contained in the flag bag.

Supporting plate 14 is conveniently bent to provide an inclined portion 16, to which is secured a battery of fingers 17, which are uniformly spaced from one another (see Fig. 2), and which are so placed in respect to name plate 15 that their spaces are below the respective insignias marked on the name plate, and indicating the flags and pennants supported from the rings and hooks placed between each two adjacent fingers. Plate 14 is conveniently looped at 18 so that the cords to which rings 19 and hooks 20 are secured will remain in untangled position for ready use.

Referring to Figs. 3 to 6, the structure of the fingers will be clearly understood from these illustrations. Each of the fingers comprises a hollow casing, which is open at its bottom and which is divided by a partition 21 into inner and outer compartments 22 and 23, respectively. Inner compartment 22 is closed by an end wall 24, which is spaced from bent portion 16 of plate 14, by means of a ledge 25 provided at the top end

of the casing and side wall extensions 26. Outer compartment 23 is closed by end wall 27. (See Figs. 3 and 4.)

Each of the compartments is provided with a pair of slots extending from the top of the structure to near the bottom edge thereof, and are disposed directly opposite each other as clearly seen in Fig. 2. Slots 29 of inner compartment 22 are tapered and are wider than slots 28 of the outer compartment, which latter slots have parallel sides.

Attention is now called to the side wall construction of the two compartments shown in Figs. 5 and 6. It will be observed that the wall thicknesses of the two compartments differ. The walls of both compartments are tapered, but the tapers 31 of the interior wall surfaces in the inner compartment 22 are inclined less steeply than tapers 30 of the inner wall faces in the outer compartment 23. The purpose for this difference in the incline will presently become evident.

Extending through aligned apertures provided in the lower portions of outer end wall 27, partition 21, and inner end wall 24 of the finger is an attaching element 32 in the form of a long flat-head screw, the threaded end of which passes through plate portion 16 of plate 14 and is secured thereto by a nut, a washer and a lock washer, as clearly indicated in Figs. 3 and 4. Another securing element in the form of bolt 33 engages a threaded aperture provided in ledge 25. By these two attaching elements the fingers are securely held in their required position.

Within pockets or compartments 22 and 23, and supported by screw 32, are springs 34, shown in detail in Fig. 7. These springs are composed of two coils 35, adapted to be slipped over bolt 32, and from which coils extend U-shaped legs 36 and 37. Leg 36 is continuous, while leg 37 represents the ends of the spring. The parallel portions of the U-shaped ends are provided with rollers 38, which are adapted to minimize friction and also serve for joining the ends of the spring leg 37.

In consequence of the difference in the wall tapers of the two compartments, spring devices 34 will assume different positions, depending upon into which of the compartments they are placed. Thus a spring mounted in inner compartment 22 will have its parallel, roller-equipped portions of legs 36 and 37, at their normal position, nearer to each other than those of a similar spring mounted in outer compartment 23, as is clearly indicated in Figs. 5 and 6, respectively. The purpose of this difference in the leg positions of the two springs is to assure the correct engagement and accommodation of the rings and the hooks in their respective slots. Rings 19 are larger in diameter than the loops of hooks 20. Both have to readily slip into and out of the fingers with the same ease, and both have to be held within the fingers with the same security against accidental disengagement. By providing a greater movement of the springs in the ring compartments, and a shorter spring movement in the hook compartments, which movements are limited by the difference in the wall thicknesses of the two compartments, the aforesaid requirements are effectively met.

It has been mentioned that the hook-receiving slots 28 of the inner compartment are tapered, whereas ring-receiving slots 29 of the outer compartment are narrower and have parallel sides. The reason for tapering of the inner slots is to facilitate the ready insertion and removal of the

hooks, the loops of which are tapered and broader at the top, and which tapered slots are further away from the operator than the narrower ring slots.

Attention is called to the fact that all corners of the finger casings are carefully rounded so as to avoid any sharp edges which may tear or otherwise damage the flags and the pennants, when the latter are either removed from or replaced into the flag bags.

While only one specific structure of my device is illustrated, containing but two compartments, it is obvious that fingers with a greater number of compartments, or with only one compartment 15 may be made, and that other changes and improvements may be incorporated therein, as may become necessary in the course of manufacture of the device. I therefore reserve for myself the right to make such changes and improvements, 20 without departing from the broad scope of my invention, as defined in the annexed claims.

I claim:

1. In a tension holder for rings, hooks and the like, a hollow structure having at least two 25 compartments open at the bottom, each compartment having inwardly tapering side walls and a pair of oppositely disposed slots in the walls, which slots are closed at their bottom, an attaching member passing through the compartments, and resilient means in each compartment supported by the attaching member for the engagement of such rings, hooks and the like, and adapted to normally bear against the tapering walls of the respective compartments.

2. In a tension holder, as set forth in claim 1, the incline of the tapered walls of one compartment being greater than that of the walls of the other compartment, the sides of the slots in the compartment having thicker walls being inclined.

3. In a finger battery for flag bags, a plurality of uniformly spaced fingers arranged in a row, each finger comprising a hollow structure composed of inner and outer compartments open at 45 the bottom, upwardly tapering slots, open on top and closed at the bottom, provided opposite one another in the side walls of the inner compartment, similar slots with parallel sides provided in the side walls of the outer compartment, the 50 walls of both compartments tapering inwards from their bottom edges towards their tops, the incline of the tapered walls of the inner compartment being greater than that of the tapered walls of the outer compartment, an attaching element for the finger passing through the end walls of and the partition between the compartments, a resilient member, designed to bear against the upper portions of both tapered walls in each compartment and being supported by 55 said attaching element.

4. In a finger structure, a hollow, downwardly opening, casing divided into at least two compartments, each being provided with oppositely disposed pairs of slots at their side walls, at least 65 one attaching element passing longitudinally through the casing, another attaching element adapted to engage one end wall of the casing, coil springs supported in each compartment by the first mentioned attaching element, said springs having end legs provided with friction-reducing means bearing against the upper portions of the side walls of each compartment in rear of their slots, the interior wall surfaces of the compartment being thicker on top and tapering downwardly, the tapers of the walls of two adjacent

compartments differing in their incline, thereby defining the normal position of the respective friction-reducing means in each compartment.

5. The combination of at least two relatively closely adjacent finger structures extending at right angles from their support and serving for the reception of rings, hooks or the like, each structure comprising a hollow, downwardly opening casing, each casing having at least two adjacent compartments, each compartment being provided with means for accommodating rings, hooks or the like, the ring and hook accommodating means of the one casing facing those of the adjacent casing, tension means in cooperation with said accommodating means and adapted to forcibly engage and removably hold such rings, hooks or the like, friction-reducing means provided with said tension means, and a

casing attaching element supporting said tension means.

6. In a finger structure, a hollow, downwardly opening casing comprising at least two compartments having side walls, the latter having oppositely disposed slots, closed at the bottom, said slot serving for the reception of rings and hooks, at least one attaching element passing lengthwise through the compartment, resilient means supported by said attaching element and disposed within each of the compartments and adapted to exert pressure in a lateral direction and to bear against such rings or hooks held in the slots, and means within the compartments for limiting to a different degree the lateral movement of their respective resilient means.

JOSEPH F. FAUNER.
